UNITED STATES PATENT OFFICE.

HERMANN TOASPERN, OF BROOKLYN, NEW YORK.

UPRIGHT-PIANO CASE.

SPECIFICATION forming part of Letters Patent No. 352,280, dated November 9, 1886.

Application filed April 8, 1886. Serial No. 198,204. (No model.)

To all whom it may concern:

Be it known that I, HERMANN TOASPERN, of the city of Brooklyn, in the county of Kings and State of New York, have invented 5 certain new and useful Improvements in Upright Pianos, of which the following is a full, clear, and exact description.

My invention consists of the combination, with an upright piano, of a music-holder arranged below the key-board and adapted to be swung outward for convenience in putting away and removing sheets of music.

Reference is to be had to the accompanying drawings, forming part of this specification, in which similar letters of reference indicate 15 corresponding parts in both the figures.

Figure 1 is a perspective view of an upright piano having a music-holder applied thereto in accordance with my invention; and Fig. 2 20 is an end view of the same, showing the music-holder open in full lines and closed in dotted lines.

The frame or case A of the piano is of the ordinary construction. B represents the music-holder. This is in the form of a falling panel 25 arranged below the key-board and above the pedals and hinged by the hinges *a a* to the bottom C of the piano-case. Upon the inner surface of the panel are formed several boxes or receptacles, D D, of a size appropriate to 30 receive sheets of music. These boxes or receptacles are formed by the inner board, *b*, two end boards, *c c*, partitions *d*, and a bottom board, *e*. (Shown in dotted lines in Fig. 2.) 35 A spring latch or lock, *f*, is fitted at the center of the panel for holding or locking the music-holder in closed position, and to prevent the holder from being opened out too far I attach the cord, wire, or tape *g* to the

casing of the piano and to the holder, which 40 limits the outward movement of the holder, as shown clearly in the drawings.

By placing the music-holder, as described, to close into the casing, it occupies what has hitherto been waste space in the piano-case, 45 and it preserves the music from dust and injury and is very convenient.

I am aware that music-holders have been formed in the front at the ends each side of the pedals of organ-cases, as in the patent to 50 G. Nettleton, July 11, 1882, wherein the case is especially constructed with chambers to contain the music-holder; and I am aware also that music-holders have been formed upon the front panel of the cases of musical instruments, as in the patent to W. W. Hyde, February 22, 1881, and do not therefore claim 55 the same. By my construction I avoid all change in the outward appearance of the instrument-case and avoid expense, as the panel 60 B is the ordinary front panel of the case, simply hinged to the base C, and provided upon its inner surface with the receptacles for the music.

Having thus described my invention, I claim 65 new and desire to secure by Letters Patent—

The music-holder B, forming the ordinary front panel of the case of the piano, located 70 between the pedals and the key-board and hinged to the base C, between the end uprights of the case, and provided upon its inner surface with partitions for forming the music-receptacles D, substantially as described.

HERMANN TOASPERN.
